UNITED STATES PATENT OFFICE.

HENRY FRED. MOLKENBUR, OF ST. PAUL, MINNESOTA.

PACKAGE-FASTENER.

1,116,904.

Specification of Letters Patent. Patented Nov. 10, 1914.

Application filed May 22, 1914. Serial No. 840,245.

To all whom it may concern:

Be it known that I, HENRY F. MOLKENBUR, a citizen of the United States, and resident of St. Paul, in the county of Ramsey 5 and State of Minnesota, have invented certain new and useful Improvements in Package-Fasteners, of which the following is a specification.

My invention relates to ties for holding a 10 number of articles together, such as envelopes, files, and the like, and the main object thereof is to provide such means which render the packaging operation very quick and secure, as also the untying thereof, 15 which dispense with the necessity for knots in the twine or cord, and which employ the articles bound into a package for the twine securing means.

My invention is fully described in the following specification, of which the accompanying drawings form a part, in which the same reference characters are used to designate the same parts in each of the views, and in which:—

25 Figure 1 is a perspective view of a plurality of flat articles secured together by means of my fastener; and Fig. 2 is a view of the fastener, detached from the package.

In the drawings forming a part of this 30 application I have shown a package *a* of a plurality of flat articles, such as envelopes or the like, secured together by means of a fastener consisting of a flat tongue *b*, having one end of a length of twine *c* tied thereto 35 at *b*², permanently, said tongue being, in this form, provided with a reduced neck portion at *b*² to prevent the twine from slipping from the same, but I may provide an eye in the outer tongue end, if desired, or any other 40 equivalents may be employed.

In practice, the tongue is inserted between any two of the packaged articles, preferably at about the approximate center of the package, as shown at *a*², and is forced into said 45 package for the full tongue length up to the reduced neck member *b*², after which the twine is passed tightly around the package and then wound one or more turns around the neck portion *b*² of the tongue *b*, the free 50 end of the twine being then passed between any two of the packaged articles and drawn tightly across the package, whereby said

free end projects beyond the side of the package opposite the portion *b*² of the tongue, this being clearly illustrated in Fig. 55 1, and said free end of the twine is firmly held against accidental removal from the package by the binding effect thereof of the adjacent packaged articles, the turns around the tongue serving to prevent the 60 withdrawal of said free end by the tendency of the package to expand, and the package is firmly bound without the necessity for knotting the twine, either to itself or to the fastener. 65

When it is desired to untie the package, all that is necessary is to manually draw the free end from between the packaged articles, sufficient end being left for this purpose, unwind the turns from the tongue, and the 70 package is unfastened, and the articles free of the fastener, both the fastening and unfastening being accomplished in the twinkling of an eye, and in a highly efficient manner. 75

The tongue is preferably very thin so as not to occupy much room between the articles of the package, and the abutting end is made as short as convenient so as not to project from the package to an appreciable 80 extent, just enough projecting to permit one or two turns of the twine around the same, and while I have shown a present preferred form of the tongue, I do not limit myself thereto, as many other forms may be used 85 in just as efficient a manner, and, with a reservation to myself of all such changes in and modifications of the form shown and described as may come within the scope of the following claim— 90

What I claim as new, and desire to secure by Letters Patent, is:—

A package fastener, comprising a tongue member of sheet material having a reduced neck member, and a cord in permanent engagement, at one end thereof, with said reduced neck member. 95

In testimony that I claim the foregoing as my invention I have signed my name in presence of the subscribing witnesses.

HENRY FRED. MOLKENBUR.
